CLAIM

The ornamental design for an automatic battery water filler, substantially as shown and described.

DESCRIPTION

FIG. 1 is a right side elevational view of an automatic battery water filler showing my new design;

FIG. 2 is a left side elevational view thereof with the filler tube being broken away for convenience of illustration;

FIG. 3 is a top plan view of FIG. 2;

FIG. 4 is a bottom plan view of FIG. 2;

FIG. 5 is a rear elevational view of FIG. 2;

FIG. 6 is a front elevational view of FIG. 2;

FIG. 7 is a front elevational view of the dispensing nozzle portion thereof;

FIG. 8 is a top plan view of FIG. 7; and

FIG. 9 is a bottom plan view of FIG. 7.

FIG. 3

FIG. 4

FIG. 8

FIG. 7

FIG. 9

FIG. 5

FIG. 6
